UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

TROLLEY-CONDUCTOR INSULATOR.

Application filed November 28, 1923. Serial No. 677,432.

To all whom it may concern:

Be it known that I, SAMUEL S. MATTHES, citizen of the United States of America, residing at Mansfield, in the county of Rich-
5 land and State of Ohio, have invented cer-
tain new and useful Improvements in Trol-
ley-Conductor Insulators, of which the fol-
lowing is a specification.

My invention relates to insulators and has
10 particular reference to that class of insu-
lators used in connecting electric trolley
lines wherein it is desired to sectionalize the
trolley wire or conductor.

One object of my invention is to provide
15 a device to be inserted between adjacent ends
of the interrupted trolley conductor to in-
sulate and maintain the adjacent sections in
insulated relation.

Another object of my invention is to pro-
20 vide a device which can be operated over by
either the wheel type of current collector
or the sliding bow type of current collector,
sometimes called a pantograph collector.

Still another object of my invention is to
25 provide a device in which all arcing is elim-
inated when a sliding type of current col-
lector passes under the device.

Still another object of my invention is to
30 provide a device for insulating adjacent sec-
tions of a trolley conductor in which unusu-
ally high voltage is used, such as a thousand
volts or more as against an ordinary voltage
of approximately five hundred volts. My
35 device, however, can be used equally as well
on the lower voltage as well as the higher
voltage.

My invention has particular advantages
40 for use on such systems as are regularly op-
erated with the sliding type of current col-
lector and which may occasionally be op-
erated over by cars using the wheel type of
current collector for the reasons set forth in
45 the third object above.

As there is a considerable bending moment
45 placed on a device of this character and as
this bending moment is greatest at the center
of the device, I have interlocked some
of the parts so that if the device should
break or become badly ruptured at a point
50 approximating the center, that the device
will still be maintained with its parts in
sufficient relation to prevent a complete sep-
aration and the separated parts falling to
the ground.

55 In the drawing accompanying my inven-
tion:—

Fig. 1 is a top plan view of one embodi-
ment of my invention.

Fig. 2 is the side view in elevation of
Fig. 1.

Fig. 3 is a sectional view of Fig. 2 taken
on the center line 3—3 of Fig. 2.

In the construction of the device disclosed
in the drawing, I employ the insulating
member 1 preferably made of wood as it is
easily formed to shape, is strong, durable
and inexpensive although other suitable ma-
terials such as fiber, etc. may be used. To
each end of the member 1 is secured an end
member 2 having spaced clevis members 3
between which is positioned the end of the
member 1 and secured thereto by the through
bolts 4. Each end member is also provided
with means 5 to receive the interrupted ends
of the trolley conductor 6. Each end mem-
ber is also provided with means 7 to receive
a conductor 8. Means 7 is old and well
known and usually comprises a cylindrical
recess to receive the end of the cable 8 and
set screw to hold the end of the cable 8 in
place. The lower face of each end member
2 is provided with a downwardly and longi-
tudinally projecting rib 9 so arranged that
it forms a continuation of the conductor 6
and provides a track for the wheel or slid-
ing collector in passing from the conductor
on to the device. Between the inner ends of
the members 9, in line with the same and se-
cured to the member 1, is a rib 10 of insulat-
ing material such as wood, fiber, porcelain
etc. which acts as a means of transfer of the
wheel collector in passing across the break
between the members 9 and is usually of the
same cross section as the member 9.

Secured to the insulating member 1, and
on each opposite side and laterally spaced
therefrom and in parallel relation, is a guide
member 11 of metal. The guide member 11
may be of the same material and cross sec-
tion as the member 6 or it may be of other
material, preferably metal however, and of
other cross section. Each guide member is
secured to the member 1 by supports com-
prising a through bolt 12 upon which is se-
cured an auxiliary insulator 13. Secured to
the auxiliary member 13 is a clamping mem-
ber 14 provided at its upper part with means
for engaging the insulating member 13 and
provided at its lower end with means for
gripping the guide member 11. I prefer to
make the auxiliary insulator members 13 of
porcelain or moulded composition in order

to provide a better insulating medium between the guide members. I find this advisable as it permits me to cut down the length of the device when used with the higher voltages, as the auxiliary insulating members 13, when composed of porcelain, moulded composition etc., offers higher insulating value between the parts.

The lower face of the guide members 11 is somewhat lower than the lower edge of the member 10 and the ends of the members 11 are turned upwardly to permit a sliding current collector of the bow type to pass from the end member on to the adjacent guide member without jar. As the bow collector passes on to the guide member 11, it is depressed below the lower edge of the member 10 and therefore does not cause any wear upon this member. The outer end of each guide member 11 overlaps the inner end of its adjacent member 9 and the members 11 overlaps each other for a considerable distance of their total length, therefore a bow trolley shortly after engaging one of the members 11 will also engage the other member 11 in its passage across the break until it has practically reached the opposite end of the break when it will pass on to the member 9.

In order to prevent arcing as the bow collector passes across the break, I connect the outer end of each guide member 11 to its adjacent end member 2 by means of the conductor 8 which is fastened to the end member 2 by the means 7 and to the clamping member 14 by the means 15, which is similar to the means 7.

It will be seen that, while the bow collector engages the two guide members 11, that the bow will be receiving current from both sections of the trolley wire and that the sections will be connected electrically during the short period of time that the bow collector is passing across the break but that the sections are insulated from each other at all times. As the difference of potential between the members 11 is very small, excepting under very infrequent occasions, there will be practically no arcing as the bow passes over the break.

As the tension strain upon the device in a longitudinal direction is at the lower edge of the member 1, the tendency is for the beam to be bent and in time rupture. The greatest bending moment is about the line 3-3 in Fig. 2. By having the inner members 12 interlocked, I find that if there is a liability of the member 1 breaking, that the interlocking with the members 12 tends to reduce this liability and will also tend to prevent the parts entirely separating if the member 1 should break.

There are many modifications to the preferred form of my invention herein disclosed which will be evident to those skilled

in the art, therefore I do not wish to be limited to the particular structure shown other than by my claims.

I claim—

1. A section insulator comprising in combination, an insulating member, an end member secured to each end of the insulating member, a pair of laterally spaced guide bars in insulated relation and having their inner ends overlapping and to be engaged simultaneously by a current collector, air insulation separating said guide bars from each other and from the insulating member and means to secure said guide bars in said relation, each guide bar being electrically connected to one of the end members.

2. A section insulator comprising in combination, an insulating member, an end member secured to each end of the insulating member, a pair of laterally spaced, air insulated and overlapping guide bars, one of which is electrically connected to one of the end members and auxiliary insulating members secured to the insulating member and interposed between the insulating member and the guide bars and to which the guide bars are secured.

3. A section insulator comprising in combination, an insulating member, an end member secured to each end of the insulating member, a pair of laterally spaced and overlapping guide bars mounted on the insulating member in insulated relation and auxiliary insulating members having a higher specific resistance than the insulating member and secured thereto and means to secure the guide members to their respective auxiliary insulating members and each of the end members connected to a guide member.

4. A section insulator comprising in combination, a single insulating member, an end member secured to each end of the insulating member to receive and hold in fixed and insulated relation the adjacent ends of an interrupted trolley conductor, laterally spaced parallel, overlapping and insulated guide bars secured to the insulated member at alternating points in a longitudinal straight line and electrically connected to the end members as and for the purpose described.

5. A section insulator comprising in combination, a single insulating member, an end member secured to each end of the insulating member and adapted to receive the adjacent interrupted ends of a trolley conductor, a pair of parallel and insulated guide members secured to the insulating member and laterally spaced therefrom, one end of each guide member extending beyond the inner end of an end member and secured to the insulating member adjacent to said end member and the other end of each guide member extending beyond the center of the

insulating member in the direction of and to a point intermediate of the inner end of the opposite end member and secured to the insulating member at a point between the center and last mentioned end member.

6. A section insulator comprising in combination, an insulating member, an end member secured to each end of the insulating member and adapted to receive the adjacent interrupted ends of the trolley conductor, a pair of laterally spaced, parallel and insulated guide members mounted on the opposite sides of the insulating member, auxiliary insulating members interposed between the guide members and the insulating member, means to secure the auxiliary insulating members to the insulating member and means to detachably engage the guide

members and the auxiliary insulating members to secure the guide members to their respective auxiliary insulating members.

7. A section insulator comprising in combination, an insulating member and an end member secured to each end of the insulating member to receive and hold in fixed and insulated relation the adjacent ends of an interrupted trolley conductor, a pair of guide bars disposed on opposite sides of the insulating member and spaced therefrom and insulated from each other, and means formed by and between said bars to act as guides for the current collector in passing over the break between the end members.

In testimony whereof I affix my signature

SAMUEL S. MATTHES.
